UNITED STATES PATENT OFFICE.

WILFRID LUMLEY, OF CONNEAUT, OHIO.

SHADE HOLDER.

Application filed September 29, 1919. Serial No. 327,300.

To all whom it may concern:

Be it known that I, WILFRID LUMLEY, a citizen of the United States, residing at Conneaut, in the county of Ashtabula and State 5 of Ohio, have invented a certain new and useful Improvement in Shade Holders, of which the following is a full, clear, and exact description.

This invention relates to a shade holder 10 for lamps, and has for its object to provide a shade holder composed of parts which can be quickly assembled and disassembled to permit the application or removal of the shade, and which can be readily and inexpensively produced, but at the same time 15 holds the shade securely but yieldingly in position without danger of breakage by mechanical pressure, or by expansion or contraction due to temperature changes.

20 The above is accomplished by my invention which comprises an annular fixture with a yielding shade engaging member, a locking ring adapted to be screwed or otherwise applied onto the fixture, together with a 25 retaining ring, preferably a split flat ring adapted to be supported by the locking ring and to encircle the neck of the shade, said locking ring serving to elevate the retaining ring into clamping engagement with the fixture, and at the same time to press the shade 30 against the yieldable member of the fixture.

The invention may be further briefly summarized as consisting in certain novel details of construction, and combinations and 35 arrangements of parts which will be described in the specification and set forth in the appended claims.

In the accompanying sheet of drawings, Fig. 1 is a side view of a shade holder embodying my invention, parts being in section; Fig. 2 is a view looking toward the under or inner side of the annular fixture with the other parts removed; Fig. 3 is a view looking at the locking ring with the 45 retaining ring in position; Fig. 4 is a detail sectional view of the locking ring; and Fig. 5 is a plan view of the retaining ring.

My invention comprises an annular fixture 10 which may have any configuration, and 50 may be designed to be supported on a ceiling, on a wall, or on a rod, chain, or other device designed to support the lamp. This fixture has an externally threaded flange 10^a, at the free end of which is an unthreaded 55 portion in the form of a skirt 10^b. Secured

in the flanged end of the fixture is a yieldable shade engaging member 11, preferably in the form of a collar or sleeve-like member turned outwardly at its shade engaging end, and slotted at intervals to form yielding fingers which terminate a short distance above or from the end of the skirt 10^b.

Adapted to be screwed onto the externally threaded flange 10^a is a locking ring 12 having at one end an inwardly extending flat 65 flange 12^a, and provided preferably with a tapered neck 12^b which extends from the flange to the threaded portion. Though the tapered part has a twofold function in my improved shade holder, I do not regard it as 70 essential to the invention in its broader aspects.

The shade holder includes in addition to the above parts, what may be termed a retaining ring 13, consisting of a flat ring of 75 metal, split or divided so as to form two adjacent ends, one of which is preferably tapered, as shown at 13^a. The external diameter of this retaining ring is such that it will rest on the inturned flange 12^a of the locking 80 ring, and will be centered thereon by the tapered part 12^b. The internal diameter of the retaining ring is such that it will encircle the reduced neck portion 14^a of the shade 14, the outturned lip or flange of the 85 neck being somewhat smaller in external diameter than the annular opening formed by the inturned flange 12^a of the locking ring.

In assembling the parts of the shade holder, the neck of the shade is extended up into the locking ring which will then be off the externally threaded flange of the fixture 10. Then the split retaining ring is placed between the out-turned lip on the neck of the shade, and the inturned flange of the locking 90 ring. To do this the tapered end 13^a is first inserted down between the shade and the flange of the locking ring, and the entire ring is then progressively inserted by turning or working the retaining ring around 95 until the ring drops into place. The retaining ring now rests on the inturned flange of the locking ring, and it supports the shade since the flanged end of the neck of the shade is too large to pass through the 100 ring. Then to fasten the shade to the fixture, the locking ring is screwed onto the externally threaded flange of the fixture until the upper surface of the retaining ring is 105 solidly clamped against the end of the skirt 110

10^b of the fixture. This positively stops further movement of the locking ring, and does away with the necessity for any auxiliary fastening device to limit its movement in a locking direction. As the locking ring is screwed into place on the fixture, the neck of the shade is pressed against the yieldable member 11 inside the fixture, and when the locking ring reaches its final position, the 10 globe is pressed firmly but yieldingly between the retaining ring and the yieldable member 11. All parts are now securely held in position, but without any danger of breakage for it is not possible to screw the locking ring tightly enough to cause dangerous mechanical pressure on the shade, and at the same time there is sufficient give in the member 11 to allow for expansion and contraction, and at the same time to afford for the shade a yielding abutment which adapts the device admirably for use in conveyances such as street cars, trains, boats and the like, where there may be considerable vibration.

25 To remove the shade from the other parts, the locking ring is unscrewed, and with a suitable tool, such as the blade of a knife, or any other convenient instrument, the tapered end of the retaining ring is lifted above the 30 flange on the neck of the shade, the tapered neck of the locking ring affording a sufficient space to enable the retaining ring to be sprung outwardly to this extent. Then by running the blade or tool progressively 35 around the retaining ring, from the beveled end to the other end, the retaining ring is gradually lifted from between the neck of the shade and the locking ring, whereupon the shade can be lowered from the locking 40 ring.

In its simplicity and effectiveness the shade holder embodying my invention is a marked improvement over devices which have been used heretofore, and especially 45 those utilizing a retaining member in the form of an endless coil spring, the use of which requires a special locking device to stop the movement of the locking ring to prevent breakage of the shade.

50 In the drawings I have illustrated the preferred construction, which may be modified somewhat, without departing from the principal features of the invention. For example, the yieldable shade engaging member 11 is an important feature of the construction when the lamp embodying the invention is used on conveyances such as cars, trains and boats, in other words, wherever the lamp is subjected to vibration, but this 55 feature could be eliminated where the lamp is used under circumstances such that vibration is absent. Furthermore, while one end of the retaining ring 13 is preferably 60 tapered, as before stated, the tapered feature 65 of this ring might be eliminated, though its

provision adds materially to the ease with which the parts can be assembled or disassembled.

Having described my invention, I claim:

1. A shade holder comprising an annular fixture, a locking ring adapted to be positioned thereon, and a retaining member loosely encircling the neck of the shade and rigidly clamped in said loosely encircling position between opposing parts of the fixture and locking ring. 70 75

2. A shade holder comprising an annular fixture provided with a yieldable shade engaging member on the interior thereof, a locking ring adapted to be applied to the fixture member, and an annular retaining ring carried by the locking ring and adapted to encircle the neck of the shade and to press the shade against the yieldable member of the fixture when the locking ring is applied 80 85 to the fixture.

3. A shade holder comprising a fixture with a threaded portion, a threaded locking ring adapted to be screwed onto the threaded portion of the fixture and provided with 90 an inturned portion, and a retaining member resting on said inturned portion of the locking ring and loosely encircling the neck of the shade and rigidly clamped in said loosely encircling position between the fixture 95 and said inturned portion of the locking ring.

4. A shade holder comprising an annular fixture with a threaded flange, a threaded locking ring adapted to be screwed onto the 100 flange of the fixture and provided with an inwardly extending flange, and a retaining member loosely encircling the neck of the shade and seated on said flange of the locking ring and rigidly clamped in loosely encircling position between said flange of the locking ring and the flange of the fixture. 105

5. A shade holder comprising an annular fixture with an externally threaded flange and a yieldable member within the flange, 110 an internally threaded locking ring having an inwardly extending flange, and a retaining member seated on said flange of the locking ring and adapted to encircle the neck of the shade and to press the same against the yieldable member of the fixture when the locking ring is screwed onto the flange of the fixture to a point such that the retaining member is clamped between the flange of the locking ring and the flange of the fixture. 115 120

6. A shade holder comprising an annular fixture having a threaded flange, a threaded locking ring adapted to be screwed onto the flange and provided with an inwardly extending portion, and a flat retaining ring adapted to encircle the reduced neck of the shade and resting on the inwardly extending portion of the locking ring, said retaining ring being split and having a tapered end. 125 130

7. A shade holder comprising a fixture with a threaded depending portion, a locking ring adapted to be screwed onto said depending portion and provided with an in-turned portion, a retaining member having opposite flat faces seated on said in-turned portion of the locking ring and adapted to encircle the shade, said retaining member extending outward underneath the extreme lower end of said depending portion of the fixture whereby the opposite flat faces of the retaining member may be clamped between the lower end of the depending portion of the fixture and the in-turned portion of the locking ring.
8. A shade holder comprising a fixture, a locking ring carried by the fixture and provided with an in-turned portion, and a shade retaining member adapted to encircle the neck of the shade and resting on the in-turned portion of the locking ring, and

adapted to be clamped between said in-turned portion of the locking ring and a portion of the fixture, the clamping face of the in-turned portion of the locking ring being at substantially right angles to the axis of the shade holder so that the clamping force on the retaining member is exerted in a direction substantially parallel to the axis of the shade holder.

9. A shade holder comprising an annular fixture having a yieldable shade engaging abutment, a shade supporting ring adapted to loosely encircle the neck of a shade and means for rigidly securing said ring to said annular fixture with the shade loosely supported in said ring and pressed against said abutment.

In testimony whereof, I hereunto affix my signature.

WILFRID LUMLEY.
